CALCULATING APPARATUS

Gerhard Rosenberg, Guildford, England

Application July 7, 1952, Serial No. 297,423

Claims priority, application Great Britain
September 13, 1951

5 Claims. (Cl. 235—71)

The present invention relates to calculating apparatus having a plurality of endless bands arranged side by side each endless band being marked on its outer surface with graduated scales showing, for example, numerals representing numbers, money, measurements or the like, the endless bands being movable manually by an operator to effect a calculation.

The object of the present invention is to provide an improved apparatus of the above kind.

According to the present invention calculating apparatus is provided which comprises a plurality of endless bands arranged side by side each being marked on its outer surface with graduated scales, a supporting sprocket wheel arranged at either end of each endless band the teeth of the sprockets engaging in perforations provided in the associated endless band, the sprockets at opposite ends of the plurality of endless bands being mounted on a pair of shafts arranged in parallel spaced relationship in a supporting framework, and means associated with each adjacent pair of endless bands for transmitting longitudinal movement from one endless band as the same moves to the limit of its scales to the adjacent endless band.

The assembly is contained within a casing having a removable or hinged lid or cover, the said cover or lid being provided with a series of parallel slots, corresponding in number to the number of endless bands, one said slot being associated with each endless band to permit a stylus or other pointed instrument to be inserted into engagement with a band whereupon longitudinal movement of the stylus will effect similar movement of the engaged endless band, the cover or lid being further provided with inspection windows one for each endless band and through which a number resulting from manipulation of the endless bands can be viewed.

The endless bands and their associated sprockets are carried by a framework which is positioned within the casing the framework comprising, for example, a pair of side members, arranged in spaced relationship with one another and between which the sprocket carrying shafts extend, a plurality of spacing members the number of which corresponds to the number of endless bands, and arranged side by side between the side members and a spacing plate arranged between the opposing edges of adjacent spacing members the components being clamped together to form a rigid assembly by clamping bolts extending between the side members the shanks of said bolts passing through aligned holes provided in the side members, spacing members and spacing plates.

Each sprocket wheel may be provided with a single set of teeth for engagement with perforations arranged along one marginal edge of the endless band, or alternatively two or more sets of teeth may be provided on each sprocket with a corresponding number of rows of perforations in the endless bands.

In order that the invention may clearly be understood and carried into effect an embodiment of the same will

2

now be described with the aid of the accompanying drawings in which:

Figs. 1 and 2 are a front elevation and side view respectively of the calculating unit.

Fig. 3 is an outside view of a casing in which the calculating unit is contained.

Fig. 4 is a sectional view on the line 4—4 of Fig. 3 and

Fig. 5 is a further sectional view on the line 5—5 of Fig. 3.

Fig. 6 is a view showing the developed lengths of the endless bands the scales on the bands being marked for money calculations.

Figs. 7 and 8 are side and end views respectively of a toothed sprocket suitable for supporting each endless band.

Figs. 9 and 10 are side and end views respectively of a toothed sprocket having modified means for engagement by the fingers of an adjacent band and

Figs. 11 and 12 are side and end views respectively of a finger suitable for use with the toothed sprocket shown in Figs. 9 and 10.

As shown in the drawings the calculating unit consists of a series of endless bands 1 arranged side by side, each band being supported at either end on a toothed sprocket 2.

The sprockets at each end of the series of endless bands are supported so as to be freely rotatable on common shafts 3 and 4 respectively arranged parallel to each other, each shaft 3 and 4 being supported at its opposite ends in side frame members 5 and 6 to which the shafts are secured by riveting their ends over into countersunk holes provided in the side members 5 and 6.

The edges of adjacent endless bands are separated from one another by separating plates 7 which are maintained in spaced relationship with one another by the interposition of spacing members 8, the side members 5 and 6, separating plates 7 and spacing members 8 being secured together to form a rigid framework by a pair of elongated bolts 9, the shank of each of which passes through aligned holes provided in the side frame member 5 separating plates 7 and spacing member 8 the threaded end of each bolt 9 being screwed into a correspondingly tapped hole provided in the side member 6.

As shown in Fig. 6 each endless band is made from a single length of metal, plastic or other suitable strip material which is provided at one end with a tongue 11, the endless band being formed by bending the strip so that the edges 12 at opposite ends of the strip abut against one another with the tongue 11 situated in contact with the inner face of the band, the ends being secured together by a rivet which passes through holes 13 and 14 formed respectively in the tongue and band.

Each band 1 is also provided adjacent one marginal edge with a series of holes 15 for engagement with the teeth of the sprockets 2, and a further series of holes 16 arranged in spaced relationship along the centre line of the band, the holes 16 being adapted to be engaged by the point of a stylus by means of which the bands are moved when effecting a calculation. Preferably each spacing member 8 is provided with a longitudinally extending groove 17 which forms a guide for the point of the stylus when inserted through the holes 16.

The sprocket shown in Figs. 7 and 8 consists of a bush 18 the length of which is equivalent to the width of the endless band. The bush has two spaced shoulders 19 and 20 on the peripheries of which the associated endless band is supported. The shoulder 20 is provided with six sprocket teeth 20a, and the reduced diameter between the shoulders provides a clearance for the passage of the rivet securing the ends of a band together so that the same will move freely when moved.

The outer surface of each endless band is provided with a plurality of scales and one unit of each scale corresponds to half the circumference of a sprocket so that movement of an endless band through a distance equal to one graduation will effect a half revolution of the sprockets supporting that endless band.

During a calculation as one endless band moves to the limit of one of its scales the adjacent band carrying the succeeding scale is moved one whole unit. For this purpose each endless band is provided at the limit of each of its scales with a finger 21, each said finger projecting sideways from the associated endless band and adapted to engage a dog member 22 formed on one end of each sprocket wheel 2.

The assembled calculating unit described above is contained within a casing comprising a base portion 23 and a removable cover 24, the cover being secured in position by screws 25 which pass through clearance holes in the side walls of the cover and base, the screws 25 screwing into tapped holes 26 provided in the thickness of the two extreme outer spacing members 3.

The cover 24 is provided with a series of parallel slots 27 the number of slots corresponding to the number of endless bands. The slots are positioned on the cover 24 so that each slot is in alignment with the longitudinal axis of the associated band to permit the stylus to be inserted into the holes 16 in the band. The cover 24 is also provided with inspection windows 28 one for each endless band and through which a number resulting from manipulation of the endless bands can be viewed.

The casing may be of metal, plastic or any other suitable material and the size of the same is preferably such that it can be carried in the pocket of the user.

The calculating device shown in Figs. 3, 4 and 5 of the drawings is designed particularly for effecting calculations in sterling.

As shown seven endless bands are provided the scales of which are marked as shown in Fig. 6. Referring to Fig. 3, the extreme right hand endless band represents the "pence" column and is provided with three scales the graduations of which are marked 0 to 11 as shown at A in Fig. 6. This endless band is provided with one hundred and eight (108) perforations 15 for the teeth of the sprocket wheels, thirty-six (36) holes 16 for the stylus and three fingers 21.

The next two bands represent the shillings column and the first of these is provided with three scales the graduations of which are marked as shown at B in Fig. 6, the other endless band being graduated and marked as shown at C Fig. 6. Endless bands B and C each have ninety (90) perforations 15 and 30 holes 16, band B also having three fingers 21, while band C has fifteen (15) trip fingers 21.

The remaining four endless bands represent the pounds columns and are identical with the endless bands B shown in Fig. 6. Three only of these endless bands are however provided with fingers 21, the same being omitted from the extreme left hand band.

The marginal edges of the slots 27 are marked according to the scales on the associated bands and each inspection window 28 is provided with a conventional symbol designating the figure shown therein upon completion of a calculation.

To prevent the band from being raised out of contact with the sprocket periphery as the fingers pass around the sprocket which could result in disengagement between the sprocket teeth and the perforations 15, the periphery of each sprocket 2 can be provided, as shown in the modification in Figs. 9 and 10, with a longitudinal groove 29 in which each finger 21' is located as it passes around the sprocket periphery. The groove 29 and the fingers 21' are complementary configured for example, toothed shaped as shown in Figs. 9-10 and 11-12 respectively to ensure positive and accurate engagement between the same. The provision of the grooves 29 has the advantage that each finger is supported against displacement relative to the

band to which it is fixed, thus the strain on joint between the finger and band is relieved during operation of the device and consequent damage to the band eliminated.

The calculator of the present invention may include different sets of endless bands the scales of which are graduated to represent plain numbers, money, linear measurements or the like.

For example, two sets of endless bands may be provided, the scales of one set representing plain numbers while the scales of the other set represent money.

What I claim is:

1. Calculating apparatus comprising a casing having a removable lid, perforated endless bands arranged side by side and each being marked on its outer surface with graduated scales, a supporting sprocket wheel arranged at either end of each endless band, the teeth of the sprockets engaging the perforations provided in the associated endless band, the sprockets at opposite ends of the plurality of endless bands being mounted on a pair of shafts arranged in parallel spaced relationship in a supporting framework removably mounted in the casing; said framework consisting of a pair of side members arranged in spaced relationship with one another and between which the sprocket carrying shafts extend, a plurality of spacing members the number of which corresponds to the number of endless bands arranged side by side between the frame side members, clamping means passing through aligned holes provided in the side members and spacing members to unite said framework in a rigid assembly; a groove extending longitudinally of the length of each spacing member for engagement by the point of a stylus to guide the same during longitudinal movement of an endless band, a series of parallel slots in the removable lid corresponding in number to the number of endless bands, one said slot being associated with each endless band to permit the stylus to be inserted into engagement with a band, inspection windows in the removable lid, one for each endless band and through which a number resulting from manipulation of the endless bands can be viewed, and means associated with each adjacent pair of endless bands for transmitting longitudinal movement from one endless band as the same moves to the limit of its scales to the adjacent endless band.
2. Calculating apparatus comprising a casing having a removable lid, perforated endless bands arranged side by side and each being marked on its outer surface with graduated scales, a supporting sprocket wheel arranged at either end of each endless band, the teeth of the sprockets engaging in perforations provided in the associated endless band, the sprockets at opposite ends of the plurality of endless bands being mounted on a pair of shafts arranged in parallel spaced relationship in a supporting framework removably mounted in the casing; said framework consisting of a pair of side members arranged in spaced relationship with one another and between which the sprocket carrying shafts extend, a plurality of spacing members the number of which corresponds to the number of endless bands arranged side by side between the frame side members, clamping bolts extending between the side members to clamp said framework components in a rigid assembly, the shanks of said bolts passing through aligned holes provided in the side members and spacing members; a groove extending longitudinally of the length of each spacing member for engagement by the point of a stylus to guide the same during longitudinal movement of an endless band, a series of parallel slots in the removable lid corresponding in number to the number of endless bands, one said slot being associated with each endless band to permit the stylus to be inserted into engagement with a band, inspection windows in the removable lid, one for each endless band and through which a number resulting from manipulation of the endless bands can be viewed, and fingers extending outwardly from one side of each endless band the number of fingers corresponding to the number of scales marked on the endless band, the fingers of one endless band being engageable with an abutment surface associated with the next

adjacent endless band to transmit longitudinal movement from one endless band as the same moves to the limit of its scales to the adjacent endless band.

3. Calculating apparatus according to claim 2 wherein the fingers of one endless band are engageable with projections formed by a dog member provided on one end of the sprocket wheels of the adjacent endless bands.

4. Calculating apparatus according to claim 2 wherein each sprocket is provided with at least one groove extending longitudinally across the periphery of the same for the accommodation of a finger as it passes around the sprocket. 10

5. Calculating apparatus according to claim 4 wherein the groove and engaging surface of the finger are of complementary configuration.
